UNITED STATES PATENT OFFICE.

WILLIAM STANLEY PENFIELD, OF SAN FRANCISCO, CALIFORNIA.

VALVE.

Application filed January 8, 1921. Serial No. 435,891.

To all whom it may concern:

Be it known that I, WILLIAM STANLEY PENFIELD, a citizen of the United States, and a resident of San Francisco, county of San Francisco, and State of California, have invented a new and useful Valve, of which the following is a specification.

The invention relates to an improved valve which is especially adapted for controlling the discharge of gasoline and the like from the tanks of motor tank-trucks such as are used in supplying gasoline service stations, stores, etc.

The primary object of the invention is to provide a valve of the character described, which will be quick acting and provide for an expeditious discharge and filling action, which will be positive, reliable and leak-proof and which will be easy to operate, durable and subject to a ready and easy disassembling for the purpose of renewing parts which have become worn or damaged.

Another object of the invention is to provide a valve of the character described which will be small, compact, and simple as to construction and comparatively inexpensive.

A further object is to provide a valve of the character described which will permit of a more rapid and reliable filling or discharging action and thereby provide for an appreciable saving in time required in the various filling operations in which the valve is used.

Another object is to provide in a valve of the character described means for supporting a receptacle in position to receive the discharge from the valve, which means is so constructed and arranged that an automatic holding of the valve in open position is effected through said means when the predetermined quantity of liquid has been discharged into the receptacle, this action being brought about by the weight of the liquid.

The invention has further objects and advantages, some of which, with the foregoing, will be set forth at length in the following description wherein I shall outline in full that form of the invention which I have selected for illustration in the drawings accompanying and forming a part of the present specification. In said drawings I have shown one form of the construction of my invention but it is to be understood that I do not limit myself to such form, since the

invention as expressed in the claims may be embodied in a plurality of forms.

Referring to the drawing:

Figure 1 is a sectional view partly in elevation of the valve of my invention;

Figure 2 is an enlarged fragmentary sectional view of a modified construction of the valve, showing the locking means for locking the valve closed.

In the present embodiment of the invention shown in the accompanying drawings, there is provided a body casting (1) shaped to provide a valve casing (2), discharge spout (3), a connection nipple (4). The nipple (4) is internally threaded and provided with a nut-like hexagonal portion (4') exteriorly thereof. The nipple is connected with the tank, not shown, in the usual manner.

The rear face of the casing (2) is formed with a screw threaded opening (5) through which a cylindrical valve seat member (6) is inserted in the assembling of the valve. The inner end of the seat member (6) is reduced and extends through a reduced portion (7) of the casing. The reductions providing abutting shoulders (8) and (9) are on the seat member and casing respectively. A gasket (10) is mounted between the shoulders.

The reduced end (7) is formed with a beveled seat (11) for a circular disk valve (12) which valve has a stem (13) reciprocally supported in an inwardly projecting boss (14) carried by the member (6). The outer end of the member (6) is closed by a wall (15) which wall carries the boss (14). The lower side of the seat member (6) is provided with a large opening (16) leading into the spout.

The stem (13) extends through the boss which boss is hollowed out as at (17). An expansion spring (18) surrounds the stem with the hollow portion of the boss and abuts a pin (19) on the stem and the boss, respectively, so as to at all times exert a force acting to close the valve. A plug (20) is turned in the opening (5) and conceals the member (6) and spring and retains these parts in place. The stem extends through a boss (21) on the centre of the plug and projects outwardly a slight distance. By removing the plug, the member (6) and valve may be readily and easily removed so as to replace worn parts or inspect the said parts.

Pivoted upon an ear (22) situated on the

upper side of the casing is an operating lever (23) of substantially an L-shape, there being provided a handle portion (24) and an operating portion (25). An intermediate part 5 of the portion (25) abuts the outer end of the valve stem. The lower end of this portion (25) is formed as a hook (26), arranged to support a bucket or other receptacle in position to receive the discharge from the 10 spout. A suitable stop lug (27) is provided on the casing to properly limit the inward movement of the portion (25) of the lever. An apertured ear (28) is provided on the 15 plug and extends outwardly beyond and close to the portion (25) of the lever. By inserting a suitable pin not shown, through the aperture in the ear when the valve is opened, the part (25) of the lever will abut the pin and be held against movement where- 20 by the valve will be held open.

As shown in Figure 2 the outer end of the stem may be apertured as at (29) so that the hasp (30) of a pad lock (31) may be inserted therethrough when the valve is closed 25 and the valve locked thus in closed position.

Operation.

When the handle of the lever is depressed 30 the valve is opened against the action of the spring but opens quickly to the leverage ac- 35 tion provided and by reason of the large valve openings and passages through the valve casing and spout, a maximum dis- charge flow results. As soon as pressure is relieved from the handle by the operator the 40 spring acts to quickly and positively close the valve so that little or no leakage and sub- sequent waste will follow.

In filling a bucket or like receptacle the 45 bail is hung on the hook portion of the lever and the spring is of such tension that the weight of the bucket is insufficient to effect the opening of the valve. However, when sufficient liquid has flowed into the recepta- 50 cle to provide the necessary weight to effect a rocking of the lever and an opening of the valve, the operator may release the handle

and the valve will be maintained in open po- 55 sition. This relieves the operator of the necessity of holding the valve handle open throughout the entire filling operation and expedites the operation as a whole.

The present type of valves used for tank- 60 trucks are comparatively slow in action and are not leak-proof. It is the main object of the invention to provide a time and gasoline saving valve which may be repaired much more easily and cheaply than the ordinary valve and will be more efficient generally.

I claim:

1. A valve of the character described em- 65 bodying in its construction a casing having an opening at one side thereof, an annular seat member withdrawable through said opening, a removable plug closing said open- 70 ing, a discharge spout extending from the casing, said seat member having an opening therein registering with the spout, a valve extending through the seat member and plug, a lever pivoted to the casing and hav- 75 ing one portion thereof abutting the outer end of the stem, a hook portion on the lower end of said lever, and a spring arranged to resist the opening movement of the valve, and means for locking the valve in closed position.

2. In a valve of the character described, a 80 casing, a discharge spout extending from the casing, an opening in one side of the cas- 85 ing, said opening being of substantially the same size as the inside of the casing, a valve seat member having a boss extending in- wardly of the opening and formed as an integral part of the seat member, a valve seat on the inner end of said member, a valve for 90 said seat, said valve having a stem extending through the boss and a plug for closing the opening in the side of the casing having an opening to receive the end of the valve stem, a spring in said boss for holding the valve upon its seat and means on the outside of the casing for unseating the valve, sub- 95 stantially as and for the purpose described.

WILLIAM STANLEY PENFIELD.
